UNITED STATES PATENT OFFICE

JESSE G. KING, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed September 28, 1927. Serial No. 222,674.

This invention relates to refrigerating apparatus, particularly to the form of refrigerating element and its arrangement in mechanical household refrigerators.

- 5 In small mechanical household refrigerating cabinets it is usual to provide a refrigerating element or evaporator which serves two purposes, cooling circulating air in order to cool the cabinet and freezing ice for table use.
- 10 In small cabinets designed to be placed in restricted spaces little space is available for the evaporator and this necessarily reduces the quantity of ice which can be frozen in the evaporator at one time. Consequently in
- 15 small evaporators it is very desirable to freeze ice quickly in order that an evaporator of such small water capacity may supply a considerable demand. It is essential, however, that the capacity for cooling circulating
- 20 air be not sacrificed to obtain a quick freezing evaporator. Evaporators of this type have been proposed having a header forming a reservoir for liquid refrigerant and depending loops of pipe, generally rectangular in shape,
- 25 which surround a rectangular enclosure or sleeve for ice-making containers. In order to freeze ice quickly it has been proposed to solder the loops against the sides of the enclosure or sleeve and then attach to the loops
- 30 fins which project outwardly from the enclosure to cool the circulating air. An objection to these evaporators is that the loops of tubing for circulating refrigerant are not in contact with the sleeve on more than two sides
- 35 because it is practically impossible to bend the tubes abruptly enough to make contact with two adjacent sides of the sleeve. This presents an obstacle to reducing the freezing time of an evaporator of a given size.
- 40 It is among the objects of the invention to provide an improved form of evaporator, particularly one adaptable to small dimensions, which will have a large ice freezing capacity, and which is effective to cool circulating air.
- 45 More specifically it is an object of the invention to provide an evaporator which is effective to cool circulating air and which has a larger heat transfer path between the ice-making receptacles and the refrigerant conduits than those heretofore known.

It is another object of the invention to provide an evaporator having the characteristics mentioned which occupies a small vertical space and which therefore can be placed in small cabinets.

55 Further objects and advantages of the present invention will be apparent from the following description, reference being had to the accompanying drawings, wherein a preferred form of embodiment of the present invention is clearly shown.

In the drawings:

Fig. 1 is an elevation of a cabinet, a portion broken away to show my improved evaporator installed therein.

65 Fig. 2 is a horizontal section on the line 2—2 of Fig. 1.

Figs. 3 and 4 are side and front elevations respectively on an enlarged scale of the evaporator shown in Figs. 1 and 2.

70 Referring to the drawings, a refrigerating cabinet 10, has a cooling compartment 11 and a storage compartment 12 separated by a partition 13. The partition has an opening 14 to permit the flow of cold air from the cooling compartment to the storage compartment and has side openings 15 for the flow of warm air from the storage compartment to the cooling compartment. Vertical baffles 16 form flues 17 which carry warm air from the storage compartment up into the top of the cooling compartment from where it flows downwardly in contact with the refrigerating element 20 and thence out the opening 14.

75 Referring to Figs. 3 and 4, the refrigerating element includes a header 21 forming a reservoir for liquid refrigerant which may be supplied to it thru a conduit 23 under the control of a float valve, not shown. Gaseous refrigerant is withdrawn from the header thru a pipe 24. The construction and arrangement of the float valve and of the apparatus for circulating refrigerant is more fully disclosed in the patent to Osborn No. 1,556,708, October 13, 1925. Depending 80 from the header are a number of vertical conduits 25 for circulating refrigerant which define a freezing space 26, within which is placed a preferably rectangular enclosure or sleeve 27 for supporting one or more ice- 85

90

making receptacles, not shown. Preferably the sleeve is provided with ledges 28 which support a removable shelf 29. When the shelf is in position two shallow ice-making 5 containers may be placed within the enclosure and by removing the shelf a single deep ice-making container can be placed therein. As noted in Fig. 4 the sleeve is spaced from the conduits 25. Preferably pairs of op- 10 posite conduits 25 are joined by an integral horizontal conduit 30 thus forming substantially rectangular loops of conduits depending from the header. The conduits 25 are placed far enough away from the sleeve 27 to permit the formation of a complete 90° 15 bend 31 between the conduit 25 and the adjacent edge of the sleeve. This permits the entire horizontal portion 30 of the loop of conduit to be placed against the sleeve. It is 20 preferably soldered to the sleeve in order to insure intimate thermal contact.

As many of the conduits 25 as are necessary are thermally connected to the sleeve 27 by vertical fins 35 which are preferably 25 soldered to the conduits 25, and as shown in Fig. 3, are provided with flanges 36 which are soldered to the sleeve 27.

Thus the sleeve is in intimate thermal contact with the loops of refrigerant conduit on 30 three sides and is therefore provided with a heat conducting path of large capacity which accelerates the freezing of water in trays placed in the sleeve. Nevertheless the portions 25 of the loops project out into the path 35 of circulating air and, as shown in Figs. 2 and 3, are separated from each other by spaces which permit the circulation of air between them. Therefore not only is ice frozen quickly but air circulating over the 40 evaporator is effectively cooled.

Furthermore, by spacing the conduit 25 laterally from the sleeve and placing the connecting portions 30 against the sleeve the overall height of the evaporator unit is ap- 45 preciably reduced. This permits successful operation in cabinets having shallow cooling compartments, such as illustrated in Figs. 1 and 2. The evaporator illustrated occupies substantially the entire height of the cooling 50 compartment. Due to the arrangement of the side flues, it is not necessary to provide space above the header for circulating air to flow over it. However it is necessary to provide a certain amount of space 40 between 55 the evaporator and the walls of the cooling compartment in order to permit the building up of frost on the evaporator without touching the walls. If frost were permitted to touch the walls, it would increase the rate 60 of heat leakage into the cabinet from the surrounding atmosphere and cause the walls to sweat. Therefore when the evaporator is referred to as occupying substantially all of the height of the cooling compartment, it is 65 to be understood that it leaves enough space

for building up frost only, and that no air circulating flues or spaces are provided.

While the form of embodiment of the present invention as herein disclosed, constitutes a preferred form, it is to be understood that other forms might be adopted, all coming within the scope of the claims which follow. 70

What is claimed is as follows:

1. A refrigerating element for refrigerating apparatus comprising in combination, 75 opposed, vertically extending conduit means for circulating refrigerant arranged to define a freezing space, a support for an ice-making container within the space and remote from said conduit means, and heat conducting fin means connecting the support and the conduit means. 80

2. A refrigerating element for refrigerating apparatus comprising in combination, 85 opposed, vertically extending conduit means 90 for circulating refrigerant arranged to define a freezing space, a support for an ice-making container within the space remote from said conduit means, and heat conducting means connecting the support and said conduit means, the heat conducting means including a plurality of fins spaced to permit the circulation of air between them. 95

3. A refrigerating element for refrigerating apparatus comprising in combination, 95 opposed, vertically extending conduit means for circulating refrigerant arranged to define a freezing space, an enclosure for an ice-making container within the space and remote from said conduit means and heat conducting fin means connecting the enclosure and the conduit means. 100

4. A refrigerating element for refrigerating apparatus comprising in combination, 105 opposed, vertically extending conduit means including a plurality of spaced tubes for circulating refrigerant arranged to define a freezing space, a support for an ice-making container within the freezing space remote from said tubes, and heat conducting fin 110 means connecting the support with the tubes. 115

5. A refrigerating element for refrigerating apparatus comprising in combination, 115 opposed, vertically extending conduit means including a plurality of spaced tubes for circulating refrigerant arranged to define a freezing space, a support for an ice-making container within the freezing space remote from said tubes and vertical heat conducting 120 fins connecting the support and the tubes. 125

6. A refrigerating element for refrigerating apparatus comprising in combination, 125 conduit means including a plurality of loops of tubing for circulating refrigerant arranged to define a freezing space, a support for an ice-making container within the freezing space, opposed portions of the loop tubing which forms the freezing space being remote from the support, and heat conducting fins 130

connecting the opposed remote portions to the support.

7. A refrigerating element for refrigerating apparatus comprising in combination, a header forming a reservoir for liquid refrigerant and a plurality of loops of tubing depending from the header and defining a freezing space, an enclosure for an ice-making container within the loops, opposed portions of the loops which form the freezing space being remote from the enclosure, and heat conducting fin means connecting the opposed remote portions to the enclosure.

8. A refrigerating element for refrigerating apparatus comprising in combination, a header forming a reservoir for liquid refrigerant and a plurality of loops of conduit depending from the header and defining a freezing space, an enclosure for an ice-making container within the loops, opposed portions of the loops which form the freezing space being remote from the enclosure, and vertical heat conducting fins connecting the opposed remote portions to the enclosure.

9. A refrigerating element for refrigerating apparatus comprising in combination, a header forming a reservoir for liquid refrigerant and a plurality of loops of conduit depending from the header and defining a freezing space, a rectangular enclosure for an ice-making container within the loops, the bottom portions of the loops being adjacent to and in intimate thermal contact with the enclosure and the sides of the loops being spaced from the enclosure, and vertical heat conducting fins connecting the enclosure to the sides of the loops.

10. Refrigerating apparatus comprising in combination, a cabinet having a cooling compartment; and refrigerating element occupying substantially the entire height of the cooling compartment including a header forming a reservoir for liquid refrigerant, an enclosure for an ice-making container beneath the header, horizontal refrigerant circulating ducts connected with the header and disposed in contact with the enclosure and means for cooling both the enclosure and air circulating downwardly beside the refrigerating device including vertical refrigerant circulating ducts spaced from the enclosure in the path of circulating air and vertical heat conducting fins connecting the enclosure to said vertical ducts.

11. A refrigerating element for refrigerating apparatus comprising in combination, conduit means including a plurality of loops for circulating refrigerant arranged to define a freezing space, a support for an ice-making container within the freezing space, the bottom portions of the loops which provide the freezing space being adjacent to and in intimate thermal contact along the bottom of the support and the sides of said loops being spaced from the opposite sides of the sup-

port, and heat conducting fin means thermally connected with the support and the sides of the loops.

12. A refrigerating element for refrigerating apparatus comprising in combination, 70 conduit means for circulating refrigerant, said conduit means being arranged to define a freezing space, a support for an ice-making container within the freezing space, the conduit means which forms the freezing space 75 including a duct adjacent to and in intimate thermal contact along the bottom of the support, said duct extending upwardly from the bottom and spaced from the side of the support, and heat conducting fin means connecting the side of the support and spaced portion of said conduit means.

In testimony whereof I hereto affix my signature.

JESSE G. KING.
